WIRE GUIDE CONTROL

Finn H. Gulliksen, Wilkinsburg, and Stephen A. Staeg, Pittsburgh, Pa., assignors to Westinghouse Electric & Manufacturing Company, East Pittsburgh, Pa., a corporation of Pennsylvania

Application January 14, 1933, Serial No. 651,722

5 Claims. (Cl. 74—241)

Our invention relates generally to the control of traveling webs to maintain them in a desired operating position.

In the art of paper making, mechanical means are provided to maintain the Fourdrinier wire in a given position on the guide roll or rolls, but such devices require considerable actuating force from the wire with the result that the wire becomes frayed at the edges. Serious breakage may thus result, and what is equally as detrimental, the useful life of the wire is materially shortened.

By the apparatus herein described and claimed in the claims hereto appended, the edge of the web whether such web be a wire, felt, paper in a printing press, or any other web, is not subject to wear.

It is an object of our invention to provide electric control means whereby the travel of a web in a machine may be kept in a substantially definite path.

Another object of our invention is the provision of mechanical and electrical control means so arranged that the mechanical control means assume the control of the web if for any cause the electrical control means becomes inoperative or is deliberately made inoperative.

A further object of our invention is the provision of electrical control means whereby the web may be controlled to selectively follow one or the other of two parallel substantially adjacent paths.

A still further object of our invention is the provision of electric control means whereby a web of material may be made to follow a given path even though a portion of the control means may have become inoperative.

Other objects and advantages of our invention will become more apparent from a study of the following specification and the claims appended thereto when considered in conjunction with the accompanying drawings, in which:

Figure 1 illustrates, more or less diagrammatically, electric control systems in combination with the conventional mechanical web guide control;

Fig. 2 is a diagrammatic showing of a photo-electric system of control for maintaining a web of material in a substantially fixed path; and

Fig. 3 is a diagrammatic showing of a modification of a photo-electric system of control such as illustrated in Fig. 2.

Referring more particularly to Fig. 1, where a system of control is shown for controlling the path of a web, 1 designates a guide roll which is but one, preferably the end roll, of a plurality of

rolls which may be shifted in angular position about the pivot point 58 by a conventional bearing shifting means shown at the left of the roll. The axis of the roll will thus take various angular positions with reference to a medium position. This shifting of the roll will effect the movement of the web towards the right or towards the left as desired.

In normal operation for printing presses, winding machines and particularly in the art of paper making the web of material, which is usually a Fourdrinier wire, for some cause has the habit of moving from the right to the left and from the left to the right, namely, meandering back and forth thus shifting its path of travel. This shifting of the path of travel is a disadvantageous action of the web and may cause breakage of the web or may cause an improper margin between the printed matter and the edge of the paper in the printing press.

Adjacent the respective edges of the web 17 are disposed a pair of rollers 3 and 18 spaced apart a distance a trifle greater than the width of the web and both rollers 3 and 18 are disposed equal distances from the desired path of travel of the web. A pair of palms 15 and 16 are also disposed at the respective edges of the web but are spaced a distance slightly greater than the distance between the rollers 3 and 18, and both palms are disposed equal distances from the desired path of travel of the web. It is thus clear that the web 17, during its meanderings, will engage either of the rollers 3 and 18 before it will engage either of the palms 15 and 16.

The palms 15 and 16 are mounted on a bar 4 which actuates a bell crank lever 5 and thus affects the movement of the left hand bearing 59 of the roller 1 in a well known manner. The palms 15 and 16 are however also interconnected with a system of control whereby the operation of the machine provided with the control system may be arrested when the web has deviated from its desired path to an extent to engage either one of the palms 15 or 16.

During normal meanderings of the web, either the roller 3 or the roller 18, as the case may be, is engaged by the web 17 thereby affecting the movement of the bearing before the palms 15 and 16 are engaged. This controlling action can probably be best understood by a study of the sequence of operation of the entire control system.

If it be assumed that the web 17 is travelling in the direction indicated by the arrow on the web, namely, that the main machine is oper-

ating, being driven by a suitable source of motor power not forming part of our invention and it also be assumed that conductors 21 and 26 are suitably energized from a source of alternating current power, then an energizing circuit is established from conductor 21 through the primary winding 22 of the transformer 23, conductor 24, contact member 25 of circuit breaker 19 to the conductor 26. Since the primary winding 22 is energized, the secondary winding 27 will be energized, thus energizing the conductors 28 and 29.

As a part of the control system, a source of direct current power is also utilized and this source of direct current power is connected to the buses 43 and 47. Buses 43 and 47 being energized, a circuit is established from bus 43 through resistor 48, conductor 49, back contact members 50 of the control relay 8, back contact members 51 of control relay 8 and conductor 52, to the energized bus 47. Another circuit is established from the bus 43 through resistor 44, neutralizing coil 45 of the time limit relay TL and conductor 46 to the bus 47. The time limit relay TL is also provided with a magnetizing coil 53 but since the back contact members 50 and 51 are closed, the magnetizing coil 53 is shunted and in consequence the time limit relay will not have operated at this stage of operation.

As the web 17 meanders back and forth on the roll 1, it will come in contact with either the roller 3 or the roller 18 if its meandering exceeds a predetermined value. If web 17 makes contact with roller 3, a circuit is established from the ground G through conductor 29, principal electrode 30 of electric discharge device 7, control electrode 31, resistor 33, roller 3, web 17 to the bearing of the guide roll 1 and back to the ground G. Since conductors 28 and 29 are energized, the establishment of the circuit between the roller 3 and web 17 changes the bias of the control electrode 31 and thus causes the electric discharge device to break down. A breakdown of the electric discharge device 7 establishes a circuit from conductor 29, through the principal electrodes 30 and 34 of the discharge device 7, the actuating coil 35 and the condenser 36 of the control relay 8 and conductor 37 to the energized conductor 28.

Operation of the control relay 8 establishes a circuit from the energized conductor 21 through conductor 38, actuating coil 39 of the magnetic device 12, conductor 40, contact members 41 of control relay 8, and conductor 42 to the energized conductor 24. Energization of the coil 39 causes the movement of the bar 4 towards the left through the interconnecting link 57 and in consequence the left hand bearing of the roll 1 is shifted in such a direction as to cause the web to travel to its central position, that is, towards the right and away from the roller 3.

Before the circuit for the control electrode 31 of the tube 7 is interrupted at the roller 3, the time limit relay TL will close its contact members 55 since the operation of the control relay 8 opened the shunt for the magnetizing coil 53 at the contact members 50. With the operation of the time limit relay, a circuit is established from the energized conductor 38 through both of the centering coils 13 and 14 of the magnetic device 12, conductor 54, contact members 55 and conductor 56 to the energized conductor 24. As long as coil 39 is energized the effect of coils

13 and 14 will not center the bar 4. This is a desirable operation because the left hand bearing is to be shifted as long as the web makes contact at the roller 3. However, the instant the contact is broken at roller 3, the discharge at the discharge device 7 ceases and in consequence the control relay 8 is deenergized. Deenergization of the control relay 8 deenergizes the coil 39 and also shunts the magnetizing coil 53 of the time limit relay TL. After a comparatively short but predetermined interval of time, the contact members 55 move to open circuit position and deenergize the centering coils 13 and 14. However, since the coil 39 was deenergized a definite time previous to the deenergization of the coils 13 and 14, the bar 4 will be moved to its central position.

If the web should move towards the right, engaging the roller 18, the bias of the control electrode 65 of the tube 6 is changed by the circuit from the ground G through the electrodes 64 and 65, resistor 66 and conductor 67, roller 18, web 17, and guide roll 1 to the ground G. The discharge device 6 is thus caused to break down, establishing a circuit for the coil 69 and condenser 70 of the control relay 8, through the principal electrodes 64 and 68 of the device 6 and conductor 71. Operation of the control relay 8 closes the contact members 74, thus establishing a circuit from the energized conductor 38, through coil 72 of the magnetic device 12, conductor 73 and through contact members 74 to the energized conductor 42. Energization of the coil 72 actuates the bell crank lever 5 in an opposite sense than heretofore described and moves the roll 1 in such a direction as to move the web towards the left and away from roller 18. Since the control relay 8 also interrupts the shunt for the magnetizing coil 53 at the contact members 51 the action of the time limit relay TL and the recentering of the bar 4 will be the same as heretofore discussed in connection with a deviation of the web 17 towards the left.

If for any reason the system of control heretofore discussed is not fast enough in its operation or if, because of defects in the web, the web moves either towards the right or towards the left faster than the correction affected by the movement of the bearing, the palm 15 or 16, depending on the direction of motion of the web, would be engaged, thereby establishing a circuit from the ground G, through the secondary 27, conductor 28, coil 60 of the circuit breaker 19, conductor 61 and the particular palm engaged by the web 17 back to the ground G. The circuit breaker 19 is caused to operate opening the circuit for the transformer 23 at the contact members 25 and also establishing a circuit at contact members 62 for the signal 63. The attendant is thus apprised of the trouble or improper operation of the machine and may thus stop the entire machine to make the necessary adjustments. Similarly, if for some cause, both the rollers 3 and 18 are engaged, contact members 75 and 76 are moved to circuit closing position, thus energizing the circuit breaker 19 and the signal 63 in a similar manner.

In the system of control shown in Fig. 2, photoelectric devices are utilized to control the path of the web and the contact rollers 3 and 18 are dispensed with. The system of control shown in Fig. 2 may also be used in combination with the mechanical control for controlling the position of the bearing, for indicating excessive deviations, and for disconnecting the source of energy

shown in Fig. 1. However, in most cases, the mechanical system of control may be dispensed with entirely because the modification shown in Fig. 1 in itself embodies safety features which make the mechanical control scheme all but superfluous.

When utilizing a portion of the safety features shown in Fig. 1 with the modifications shown in Figs. 2 and 3 their function remains the same. 10 If the indicating or signalling means and stopping means of Fig. 1 are used with Figs. 2 and 3, their function remains the same.

In Figs. 2 and 3, if the web contacts palm 15 or 16, as the case may be, a circuit is established 15 from the grounded conductor through the machine, the particular palm that may have been contacted by the web, through actuating coil 60 of the circuit breaker 18 to the conductor 106, Fig. 2, or conductor 206, Fig. 3, depending upon 20 the system with which the indicating and stopping means are used.

Assuming that the printing press or the paper machine, as the case may be, is in operation and the web 82 is traversing the rolls 80 and 83. 25 The roll 83 may have fixed bearings 84 and 85 because it is well known that if the angular position of but one roll with reference to the axis of the other roll is changed the web may be caused to move either towards the right or towards the 30 left. Further, let it be assumed that the switches S and 25 are closed, thus connecting the energized buses 100 and 106 to the conductors 101 and 105, respectively. This operation establishes 35 circuits for the lights 109 and 111 and a circuit from the conductor 101 through conductor 102, through the primary windings 103 and 107 of the 40 transformers T and T', respectively, and conductor 104 to the energized conductor 105. Energization of the two transformers obviously 45 causes the two secondary windings 118 and 143 to place a certain potential between the cathodes 120 and 144 and the control electrodes 123 and 147 of the respective electric discharge devices shown.

50 A pair of photo-electric cells 126 and 149 is disposed adjacent the edges of the web and a pair of lights 109 and 111 is disposed to cooperate with the respective photo-electric cells. The arrangement and spacing of the lights and photo-electric 55 cells are such that light falls on both of the cells when the web is travelling in the desired path. However, if during operation the web deviates from its desired path, intercepting the light falling on either of the photo-electric cells, the bias on the respective control grid 123 or 147, as the case may be, is changed and the particular electric discharge device affected breaks down to establish a circuit for the control relay associated therewith.

60 If it be assumed that the web travels towards the left, intercepting the light passing from the source of light 109 to the photo-electric cell 126, the bias on the control grid 123 is changed and 65 in consequence an energizing circuit is established from the transformer T, through conductor 119, the principal electrodes 120 and 124, conductor 127, resistor 128, actuating coil 129 of control relay 131 and conductor 130 to the transformer 70 T. Operation of the control relay 131 causes the opening of its upper contact members to deenergize the transfer relay 134, should it be energized, and causes the closing of its lower contact members 135. Closing of the lower contact members 75 135 establishes a circuit from conductor 101

through contact members 135, actuating coil 136 of the transfer relay 133 and conductor 137 to the energized conductor 105. Transfer relay 133 establishes its own hold-in circuit through back contact members 138 of relay 132 and contact members 139.

With the operation of the transfer relay 133 the contact members 114 are moved to open circuit position, thereby causing the deenergization of the motor 89 in a manner more explicitly 10 stated hereinafter. Operation of the transfer relay 133 also causes the energization of the directional contactor R, by a circuit which extends from conductor 101, through conductor 140, contact members 141 and actuating coil 142 of contactor R to conductor 105. With the closing of the directional contactor R, the motor 89 is energized from conductor 91, contact members 92, field winding 92', the motor armature and the starting resistor shown to the conductor 91'. The bearing 86 is thus moved, through the reduction gear 88 and worm 87, so as to move the web 20 towards the right.

As the bearing 86 is shifted with reference to pivot 81 the web 82 moves toward the right, thereby ceasing to intercept the light falling on the photo cell 126. The instant the web has moved towards the right by an amount sufficient to permit the light to fall on the photo-cell, control relay 131 is deenergized. However, deenergization of the control relay 131 does not at this stage of operation stop the movement of the web towards the right, since the transfer relay 133 remains energized through its holding circuit through the contact members 138 and 139.

As the web moves toward the right, the light falling on the photo-cell 149 is intercepted and the bias on the control grid 147 is suitably changed. In consequence, the right-hand discharge device establishes a circuit from the transformer T' through principal electrodes 144 and 148, resistor 150, actuating coil 151 of relay 132, and conductor 152 to the transformer T'. Operation of the control relay 132 causes the deenergization of the transfer relay 133 by the opening of the contact members 138 of relay 132, so that the directional contactor R is deenergized. Further, closing of the contact members 153 of relay 132 establishes a circuit from conductor 101 through contact members 153, actuating coil 154 of the transfer relay 134, and conductor 155 to the energized conductor 105. The transfer relay 134 is thus actuated, causing the energization of the directional contactor L, by the energization of coil 116 thereof through contact members 157 of relay 134 and conductor 117. The web will thus be caused to move towards the left, and the web will not be reversed in its movement until it has moved to the left-hand side when the cycle of operation heretofore discussed is repeated. If for any reason automatic shifting of the web is not desired, the control relays 131 and 132 may be suitably deenergized and the direction of operation of the motor 89 may be 60 manually determined by shifting the switch 115 back and forth to successively energize either the directional contactor R or the directional contactor L by the circuit through conductor 112 and contact members 113 and 114.

In the modification shown in Fig. 3, provision is made to protect the equipment generally by a system of control which provides for the movement of the web along a certain path until, say, one of the lights fail and then the web is shifted slightly and is moved along a path parallel to the 70 75

first path and removed a short distance from the original path.

Assuming that conductors 201 and 206 are suitably energized and that the two transformers 5 T and T' shown are energized. Further assuming that the switches 208 and 215 are also closed so that the lower control circuit per se is suitably energized. From the first assumption, it will be apparent that the lights 235 and 236 are energized and that the electric discharge devices provided with a grid bias circuit embodying the two resistors 238 and 239 and two condensers 240 and 241, respectively, are also suitably energized.

At the control circuit it will be apparent that 15 an energized circuit is established from conductor 209 through conductor 210, neutralizing coil 211 of time-limit relay 221, and neutralizing coil 212 of the second time-limit relay 219, and resistor 213 to the energizing conductor 214. If it be 20 assumed that the machine is in operation, as heretofore explained in connection with the discussion of the modifications shown in Figs. 1 and 2, and that the lights 235 and 236 are suitably energized, as is apparent from an inspection 25 of the drawings, then if the web is in the proper position and, at the time under consideration, is shifting or meandering towards the left and the light falling on the photoelectric cell 234 is intercepted, the control relay 242 will be 30 energized.

That the web will, in the absence of other influences, move toward the left, is apparent from the fact that the motor armature 225 will normally rotate in such direction that the web will 35 be shifted toward the left if switch 222 is kept in the position shown. With switch 222 in the position shown, a circuit is established from conductor 209 through conductor 217, armature 218 of time-limit relay 219, armature 220 of time-limit relay 221, switch 222 and actuating coil 223 of directional contactor L to the conductor 214. A motor circuit is thus established from the conductor 209, through resistor 224, armature 225, field winding 226 and contactor 227, to the conductor 214 and the motor shifts the bearing 286 to cause the web 282 to move toward the left.

The operation of the control relay 242 establishes a circuit from conductor 209 through resistor 243, contact members 244 and 245 of relays 50 242 and 252, respectively, and magnetizing coil 246 of time-limit relay 219 to the energized conductor 214. The arrangement of the contact members for the control relay 242 is such that the upper or make contact members 244 close before the lower back contact members 247, utilized for shunting the magnetizing coil, are opened. It is thus apparent that on reverse operation a discharge path will be established 55 for the magnetizing coil 246 before the contact members 244, for energizing the magnetizing coil 246 are moved to open-circuit position.

Attention is called to the circuit established from conductor 209 through conductor 248, contact members 249 of the lower time-limit relay 60 219, and the actuating coil 250 of the directional contactor R to conductor 214. The motor 225 for shifting the bearing 286 of the roll 280 will thus be energized from conductor 209 through resistor 224, armature winding 225, field winding 292, and contact members 292 of the contactor R to the conductor 214 and the left-hand bearing 70 of the roll will be so shifted that the web will move towards the right.

For the circuits established as just discussed, 75 the web 282 will shift towards the right by an

amount just sufficient to permit the light from the light source 235 to fall on the photo-cell 234. When this happens the control relay 242 will be deenergized, closing the contact members 247 an instant before the contact members 244 are opened, thereby establishing a shunt circuit for the magnetizing coil 246, of the time limit relay 219. The time-limit relay 219 will thus remain in its energized position for a predetermined interval of time, depending upon its adjustment. After the interval of time has elapsed, the back contact members of time-limit relay 219 are closed, thereupon establishing a circuit for the directional contactor L an instant after the energizing circuit for the directional contactor R has been interrupted at the contact members 249. The web will thus be shifted towards the left until the web again intercepts the light passing from light 235 to light sensitive device 234 and causing the motor to again shift the bearing 286 so that the web is shifted towards the right.

The cycle of operation heretofore discussed is 10 repeated indefinitely, so that the left edge of the web 282 is maintained in line with the beam of light at the left side of the machine. If, for 15 any reason, the light 235 fails, the control relay 242 remains energized, whereupon the contact members 244 thereof remain closed, thereby causing the contact members 249 of relay 219 to 20 remain closed, so that the motor, through the directional contactor R, continues to operate and shift the web 282 towards the right by an amount 25 sufficient that the light passing from the light 236 to the photo-cell 237 is intercepted, whereupon the control relay 252 is energized, closing the contact members 254, 255, and opening the contact members 256 thereof. Closing of the contact members 254 does not cause the operation 30 of the time-limit relay 221 because the contact members 253 are held open by the control relay 242. However, since the control relay 252 also 35 opens the contact members 245, the time-limit relay 219 is deenergized, and after a predetermined 40 interval of time, the motor operating the bearing 286 is energized to shift the web towards the left. This is accomplished by the circuit from conductor 209 through conductor 217, armatures 45 218 and 220, switch 222 and actuating coil 223 of the directional contactor L to the energized conductor 214. The directional contactor L being 50 thus energized, causes the motor 225 to operate in such a direction as to shift the web towards the left. However, as soon as the light passing 55 between light 236 and light sensitive device 237 is not intercepted, the contact members 245 close, thereby causing the closing of the contact members 249 and 292 and the opening of the circuit for the actuating coil 223 at the back contact members of the time-limit relay 219. The web 60 will thus be shifted towards the right until the light is again intercepted at the photo-cell 237. This cycle of operation is thus repeated indefinitely as long as the light 235 has not been replaced. When that light has been replaced, the 65 left-hand photo-cell 234 is again utilized.

If, for any reason, the attendant should not notice that the right-hand light and photo-cell are utilized, and the light 236 should also fail, then both sets of contact members 257 and 255 70 would be energized, thereby energizing the signal 293 through contact members 257 and 255. With the failure of both lights, both directional contactors will, of course, be energized, but since the motor is a splitfield-series motor, it will not 75

operate, but will merely be connected across the line with the two field windings 226 and 292' acting in opposition to each other.

From the modification disclosed in Fig. 3, it is obvious that if switch 222 be shifted to the dotted-line position, the method of operation will be changed slightly, namely, initially the right photo-cell 237 will be utilized and if the light 236 should fail, then the web will be shifted towards the left and operate on the left side until the light 236 has been replaced. It should be apparent that the system of control shown and described in Fig. 3 may be utilized in combination with the conventional mechanical methods of shifting the bearing 286 now utilized, or in combination with palms 15 and 16 and the circuits associated therewith and when so combined, provide an added safety feature to prevent any shut-downs, which of necessity are dangerous and expensive in the paper making industry.

Applicants are, of course, aware that those skilled in the art, after having had the benefit of the teachings of applicants' invention, could devise other circuit diagrams and control systems for accomplishing the desirable results described in this invention, but applicants wish only to be limited by the pertinent prior art and by the scope of the claims appended hereto.

We claim as our invention:

30 1. In a control system for a machine operating on web material, the combination of, photo-electric means disposed adjacent each edge of the material, control circuits subject to the control of said photo-electric means and web-shifting means, coacting with said control circuits, for maintaining one edge of said web adjacent one photo-electric means and means, responsive to a partial failure of said control circuits, controlling said web-shifting means for shifting said 40 web of material so that its other edge is maintained adjacent the other of said photo-electric means.

2. In a control system for a machine operating on webs of material that are subject to 45 meander from a desired path of travel, a plurality of rolls for supporting and causing a web of material to travel in a given direction, photo-electric means disposed adjacent the edges of the web, lights disposed to normally act on said 50 photo-electric devices but which cease to act on said photo-electric devices when the web meanders to a position to intercept the light passing to said devices, and means responsive to the operation of said photo-electric devices for causing 55 the axis of one of said rolls to be disposed

at an angle to the axes of the other rolls to thus shift the web back to the desired path of travel.

3. In a control system for a machine operating on web material to move the web in a certain direction, in combination, web shifting means 5 for causing the web to shift to and fro transversely of the general direction of motion of the web by a small amount, and electronic means, responsive to a predetermined shift of said web, adapted to control said web shifting means to 10 cause the web to follow a given path, said electronic means including control means responsive to the failure of a part of said electronic means to cause said web to shift to and fro a small amount to thus follow another given path. 15

4. In a control system for a machine operating on web material to move the web in a certain general direction, in combination, web shifting means for causing the web to shift to and fro a small amount transversely of the general direction of motion of the web, and electronic means disposed adjacent the edges of the web and responsive to a predetermined transverse movement of the web to control said web shifting means whereby the web is caused to follow 20 a desired path of travel, said electronic means including control means, responsive to a failure of a part of said electronic means at one edge of the web, to cause said web to shift to and fro a small amount to thus follow a path parallel 25 to the first path but still within the range of the desired path. 30

5. In a control system for a machine operating on web material to move the web in a certain general direction, in combination, web shifting means for causing the web to shift to and fro a small amount transversely of the general direction of motion of the web, and electronic means comprising two groups, each group having a plurality of elements, one group being disposed at one edge of the web and the other group being disposed at the other edge of the web, said electronic means being responsive to transverse movements of the web and adapted to control the web shifting means whereby the web is caused to follow a desired path of travel, said electronic means also including control means responsive to the failure of any number of the elements of one group of said electronic means to cause the web to shift to and fro a small amount to thus follow a path parallel to said first path but still within the range of the desired path. 40 45 50 55
